TURBINE

William A. Heap, Mulvane, Kans., assignor of one-fourth to Furman Williams, Canadian, Tex., and one-fourth to Gene Howe, Amarillo, Tex.

Application March 11, 1938, Serial No. 195,223

1 Claim. (Cl. 60—13)

My invention relates to an internal combustion turbine; whether of the Diesel type of internal combustion or of the spark fired type of internal combustion, wherein substantially the entire energy resulting from the explosive or expansive action of each gaseous discharge will be converted into power.

The object of my invention is to provide an engine of great efficiency, wherein practically the entire kinetic energy or expansive force of each impulse discharged by the respective cylinders will be utilized before the spent impulse is released to atmosphere at substantially atmospheric pressure, with the result that a great economy in fuel consumption is provided.

The various objects and advantages of my invention will all be more readily comprehended from the detailed description of the accompanying drawings, wherein:

Figure 1 is a sectional view which illustrates a spark fired type of internal combustion turbine; the view being taken on the offset line 1—1 of Figure 2.

Figure 2 is a sectional view taken substantially on the line 2—2 of Figure 1, looking in the direction of the arrows.

Figure 3 is a sectional view taken on the line 3—3 of Figure 1, looking in the direction of the arrows.

Figure 4 is a sectional view taken on the line 4—4 of Figure 2, looking in the direction of the arrows.

Figure 5 is a view taken on the line 5—5 of Figure 2 looking in the direction of the arrows.

Figure 6 is a vertical sectional view illustrating a modification of the spark fired type of internal combustion turbine.

Figure 7 is a sectional view taken on the offset line 7—7 of Figure 6.

In Figures 1 to 5, I illustrate an exemplification of my improved turbine employing spark fired internal combustion cylinders contemplating the extraneous use of a suitable fuel atomizing device or carburetor for providing the explosive mixture; the mixing chamber or carburetor not being shown.

The annular shell or casing 82 is formed for passage of the shaft 29 therethrough; one end of the shaft may be provided with a suitable starting motor or other medium (not shown), while the other end is adapted to constitute the driving end or power take-off end.

Loosely mounted on the shaft 29 is a disc or wheel 83, the perimeter whereof extends between the spaced apart annular flanges 84, 84 secured to the casing.

Circumferentially spaced apart and preferably formed integral with the disc 83 are a plurality of cylinders 85 of predetermined size or bore and disposed transversely of the disc as shown in

Figure 1; the combustion ends of the cylinders being shown provided with heat dissipating fins. The combustion ends of the cylinders are also preferably formed integral with a flat ring 86 which constitutes the head of all the cylinders; there being sixteen cylinders in the embodiment illustrated.

This head forming ring 86 is held in close contact with a flat ring or annular plate 87 which is fixedly secured to the casing; the opposing faces of the head forming member 86 and stationary member 87 being preferably provided with a number of interengaging annular grooves and ribs 88 arranged on opposite sides of the ports 89 and 90 in the cylinder head plate 86 and in the stationary plate 87. The close contact between the head plate 86 and the annular plate 87 is maintained by the off-set or angular ring members 91 and 92; one side or flange of each ring being secured to the annular plate 87, while the other sides or flanges overlap the marginal portions of the head plate and through the medium of the ball-bearings anti-frictionally hold the head plate 86 in proper relation.

Each cylinder 85 is provided with a similar piston 93 whose outer end is provided with a pair of ball-bearing holding members 94, 94 and a centrally disposed ball-bearing holding extension or post 95. The outer ends of the members 94, 94 are spaced apart sufficiently to receive the web portion of a cam member 96 therebetween, with the ends of members 94, 94 extending beneath the transversely disposed cam surface 97, while the anti-friction element or ball 98 contacts the top of the cam surface, with the result that the pistons 93 will follow the contour of the cam surface.

The cam member 96 is in the nature of a ring with its base immovably secured to the end wall of the casing 82, and the web of the ring provided with the transversely disposed cam-head or surface which is of an undulating nature as shown in the fragmentary view, Figure 4.

As the cylinder carrying disc or wheel 83 is intended to rotate, it is apparent that the pistons 93 of the cylinders will be caused to reciprocate as the pistons ride the undulations of the stationarily held cam member 96.

In slight spaced relation with plate member 87 preferably is another annular plate 99 fixedly secured in place; the central portions of plates 87 and 99 being preferably provided with cut-out portions or openings for free circulation of air throughout the cylinder portion of the casing; the side wall 82^a of the casing being provided with a plurality of air admitting openings.

Keyed to shaft 29 is a rotor member or wheel with the felly of prearranged dimensions to adapt it to have the two circumferential series of vanes or blades 12, 13, of different transverse dimen-

sions and spaced apart by means of an annular radially arranged groove in the felly of sufficient depth to receive the annular ring or stator member 74, which is fixedly secured to the casing and provided with the circumferential series of vanes 76 whose dished sides face in a direction opposite to vanes 72 and 73. Secured to the casing between the rotor 70 and the end wall 82^a of the casing is another stator member 75 provided with a circumferential series of vanes 77 with their dished sides facing in a direction similar to blades 76 and, therefore, opposite to the blades 72, 73 of the rotor 70.

The transverse width of the different series of blades are of predetermined dimensions; as, for example, if the vanes or blades 72 are say a half inch in width, then the vanes or blades 76 of the adjacent stator should be approximately three-quarters of an inch; while the blades or vanes 73 on the discharging side of the stator-blades 76 should approximately be one inch in width; and the width of the blades 77 of the stator on the discharge side of the rotor-blades 73 should approximately be a half inch in width in order to somewhat "back-up" the too rapid passage of the expanding gases passed the blades 73 before the expanding action can be completely utilized.

The pistons 93 of the cylinders are preferably shown provided with small cylindrical extensions or bosses 100 adapted to fit into the ports 89 of the head forming ring 86; the purpose of this construction being to fully expel or scavenge the cylinders immediately following the explosion period.

At prearranged points, say ninety degrees apart, the stationarily held plate or flat ring 87 is provided with small chambers or pockets 101, see Figure 2, provided with inlet pipes 102 which connect with a suitable source of carburetted oil or gasoline arranged to positively feed the carburetted gasoline or other suitable atomized oil into the pockets 101. The pockets 101 are provided with arcuate outlets or slots 103 disposed through the plate 87 toward the head forming ring 86; the slots 103 being arranged to register with the ports 89 during the rotation of the cylinder carrying member 83 and the head plate or ring 86 formed integral with the cylinders.

The stationary member or plate 87, at predetermined points, correlated with the supply pockets 101, is provided with openings 90 which extend entirely through the plates and arranged in the annular plane of the slots 103 of pockets 101 so as to register with the ports 89 in the cylinder head plate or ring 86 during rotation of the cylinder carrying member or wheel 83; the opposite side of the stationary plate 87 being shown provided with the enlargements or bosses 105 which encircle the openings 90 and extend into sockets formed in the adjacent stationary plate 99 which in turn is provided with properly flared ports 105^a immediately adjacent the vanes 72 of the rotor 70 (Fig. 4); the flaring of said ports being in the direction of rotation of the rotor.

In close proximity to the ports 90, so as to also register with the ports 89 of the cylinder head plate 86, I provide suitable "hot points" 106. These "hot points" preferably consist of platinum wires insulatedly mounted in the plate 87, as for example shown in Figures 2 and 4, with the outer ends of the wires connected in a suitable circuit of current supply; platinum wires being preferably employed because the suc-

sive ignition of the compressed mixtures in the cylinders will maintain the wires at firing heat and thus obviate the necessity of make-and-break spark control.

It is apparent from the construction shown, that as the cylinder carrying member 83 is rotated (initially by any suitable well known means which may have controllable operative connection with shaft 29), the respective pistons 93 will be caused to ride the undulating surface of the cam member or ring 96, and as these undulations are disposed toward the pistons, the latter will be reciprocated in their cylinders and successively provide suction or intake periods and compression and explosion periods. For instance, in Figure 2, we will assume that the cylinder carrying member 83—which would be located to the rear of plate 87 as viewed in this figure (the web or spokes of the member or plate 83 being shown)—is rotating in clockwise direction and that the port 89 of a "fired" and discharged cylinder is being brought into register with slot 103 of the "gas" supply pocket 101 at the upper right hand of the figure. The piston of this cylinder is then beginning to ride down on one of the undulations of the cam member, causing the piston to move outwardly on its suction or intake stroke and providing the cylinder with the combustible mixture. This suction or intake period continues until the cylinder reaches the opposite end of the elongated pocket at which time the piston has reached a valley in the cam and begins to ride up the adjacent "rise" of the cam and moves through its compression stroke; this phase being indicated at C. The cam element 96 immediately adjacent the "crests," on the approaching sides, preferably is shown provided with the slight lags or "dwell" as indicated at 107. When the pistons reach these "dwell" the mixture has been fully compressed and the cylinder-port 89 has registered with the firing point or wire indicated at 106 and is also beginning to register with a discharge port 90, thus allowing the impulse to expand its energy through the vanes of the rotor. The cam surface continues upward past the "dwell" to the crests, thus inducing the pistons to complete their inward or exhaust strokes and causing the bosses 100 to force the gases out of the ports 89 in the cylinder head.

The shaft 29 may be adapted to drive the cylinder carrying member or wheel 83 through the medium of a suitable gear reduction as illustrated for example by the pinion 108, keyed on the shaft 29 and meshing with gear 109 rotatably secured on the wall of the casing and provided with a pinion 110 which meshes with a gear 111 keyed on the hub of the cylinder carrying member or wheel 83. It will be understood, of course, that any suitable means may be provided whereby the cylinder carrying wheel may be rotated at a speed commensurate with the speed of rotation of the turbine rotor 70 and its shaft 29.

In Figures 6 and 7, I illustrate a modification of the "hot point" type of combustion cylinder turbine, namely with the internal combustion cylinders arranged radially and their outlets disposed in a radial direction toward the cylindrical wall of the casing 112. The casing is shown provided with the turbine driven shaft 29 to which the rotor member 70 is keyed; the felly of the rotor member as in the previous constructions being of sufficient dimensions to permit it to be provided with the two circumferential series of blades or vanes 72 and 73 spaced apart by a deep circumferential groove into which the stator ele-

ment 74 extends with its vanes 76 in circumferential alignment with the vanes 72 and 73; while the final discharge side of the rotor extends in flush or substantially face-to-face contact with the last stator element 75 also provided with a series of blades or vanes 77; with the opposing faces of the stator members and the rotor preferably provided with interengaging annular ribs or grooves as heretofore described. The end wall of the casing adjacent the vanes of the stator 75 is, of course, provided with suitable outlet openings for discharge of the spent gases.

Loosely mounted on shaft 29 is a disc or wheel 113 which is provided with a preselected number of internal combustion cylinders 114 formed integral therewith; the heads or end wall of the cylinders being disposed in close relation with the casing 112 and provided with ports 115 which are adapted to come into register with ducts 116 arranged in enlarged portions of the casing as shown in Figure 6. The ducts 116 are arranged at predetermined points on the casing, for example ninety degrees apart, as disclosed in Figure 7; and these ducts 116 in turn continue into the stationary wall or plate 117 where they terminate in elongated throats or orifices as shown at 118 (as shown in Figure 6) disposed adjacent the vanes or blades 72 of the rotor member 70; the elongated orifice 118 being shown in the nature of a groove in the stationary wall or plate 117.

The cylinders 114 are each provided with a piston 93, similar to the pistons shown in Figure 1 and designed to perform the function heretofore described.

Immovably mounted in the casing, as for example secured to the rigidly held wall 117, is an annular cam member 119 provided at its perimeter with the transversely disposed cam surface 97 which is engaged by the jaw portions at the outer ends of each piston through the medium of suitable anti-friction elements or balls which are preferably yieldingly pressed against the cam surface by light springs mounted in recesses as indicated at 120. The cam surface 97, as in the previously described constructions, is made undulating in order to induce the desired reciprocations of the pistons as is apparent from the disclosure made in Figure 7.

At points adjacent the ducts 116 the casing is provided with fuel introducing inlets or conduits 116a leading from suitable extraneous fuel atomizing device or carburettor (not shown) the pistons 93 being reciprocated in their cylinders, by the cam surfaces 97, and successively providing suction or intake periods (for admission of fuel through inlet conduit 116a) and compression and explosion periods whereby the exploded gases are discharged through ducts 116 as previously described; and the casing, coincident with the ducts 116 is provided with "hot points" preferably of platinum wire as heretofore described and shown in Figure 2 or suitable spark producing plugs 106, except that these "hot points" are arranged in the cylindrical casing 112. The "firing" of the compressed gases occurs as the ports 115 of the cylinders reach the ducts 116, at which time the pistons have reached the slight lags or "dwell" 107 in the cam surface; the further travel to the adjacent crest in the cam surface causes the extension or boss 100 on the inner end of the piston to scavenge the cylinder.

The expanding impulses are first discharged by the elongated throats 118 of the ducts 116, onto the vanes 72 of the rotor 70, thence onto the stator blades 76, which discharge the partially expanded gases onto the vanes or blades 73 of the rotor; the too rapid passage of the gases through the rotor being prevented by the action of the stator blades 77; the spent gases being discharged from the stator 75 through suitable openings in the casing 112.

After initial rotation of the cylinder carrying member 113 by some suitable mechanism, the member 113 will be rotated and the cylinders made to move through an orbit through the medium of a suitable gear reduction between the turbine driven shaft 29 and the member 113, which may be similar to that disclosed in Figure 1 and hence need not be further described.

Several forms of the impulse generating portion of the turbine have been shown as embodiments of the invention adapted for use in the manner illustrated without regard to the many uses to which my invention may be applied and these exemplifications have been described in terms used for purposes of description and not as terms of limitation, as structural modifications are possible and may be made without, however, departing from the spirit of my invention as defined by the appended claim.

What I claim is:

A turbine of the character described comprising an annular casing with an annular immovable wall whereby the casing is divided into two compartments, the immovable wall being provided with ports arranged in a circumferential row and in predetermined spaced relation, certain of the ports being circumferentially elongated and constituting fuel supply ports while the alternate ports constitute discharge ports arranged adjacent the respective supply ports; ignition points mounted in said immovable wall adjacent and in advance of each discharge port; an annular member rotatably mounted in one compartment of the casing substantially parallel with said immovable wall; a plurality of internal combustion cylinders secured to said annular member in circumferentially spaced relation with their ported ends arranged in gas-sealing relation with said immovable wall and adapted to successively register with the ports therein; pistons reciprocatingly mounted in the cylinders and provided with jaws on their outer ends; a fixedly secured annular member mounted in the compartment of said rotatable annular member provided with an undulating cam surface arranged between the jaws of the pistons whereby the latter are reciprocated through their intake and exhaust strokes when the first mentioned annular member with the cylinders is rotated; rotor means arranged in the other compartment of the casing in gas-sealing relation with the adjacent side of said immovable wall and having circumferentially arranged vanes adapted to register with said exhaust ports in said immovable wall; and means adapted to be actuated by said rotor means and operatively connected with said first mentioned annular member whereby the cylinders are moved through an annular path at a predetermined speed correlated with the speed of rotation of the rotor means.
